CLAIM

The ornamental design for a beverage container with lid as shown and described.

DESCRIPTION

FIG. 1 is front view of a beverage container with lid showing my new design.

FIG. 2 is a rear view thereof;

FIG. 3 is a side view thereof;

FIG. 4 is an opposite side view thereof;

FIG. 5 is a top plan view thereof;

FIG. 6 is a bottom plan view thereof; and,

FIG. 7 is a perspective view thereof.

The circular elements having stipple shading are surface ornamentation and form part of the claimed design. The broken lines immediately adjacent the shaded areas represent the bounds of the claimed design; the broken lines form no part of the claimed design.
